UNITED STATES PATENT OFFICE

AUGUST W. L. HARTBAUER, OF CHICAGO, ILLINOIS

RAILWAY CAR CONSTRUCTION

Application filed March 23, 1929. Serial No. 349,380.

My invention relates to railway cars and particularly to open top cars of the dumping type wherein part of the floor comprises one or more doors hinged to the car body and arranged to be opened or dropped to discharge part of the lading.

When such doors are supported by more than two hinges it is difficult to align the hinge pins so that the door will operate freely, and furthermore, as two hinges are sufficient to support the door when in lowered position any additional hinges cause unnecessary expense and labor. However, with only two hinges the hinged edge of the door may sag or bend under an imposed load, which bending would retard the free movement of the door and also might cause a leaky car.

An object of the invention is to provide a support for the hinged edge of the door, which support is positioned between the hinges and upholds the door when it is in closed position.

A further object of the invention is to provide stiffening means adjacent the hinged edge of the door and a bracket thereon, which bracket transmits the load on the door to the support on the frame of the car.

In the drawings:

Figs. 1, 2 and 3 show a typical application of my device to a railway car.

Figs. 4 and 5 show enlarged details of the hinged edge of the door and part of the center construction of the car.

In the form of my invention illustrated the door 2 is supported upon the center construction 3 of the car by hinges 4 and extends to the side wall 5 of the car so that when the door is dropped, as shown in dotted position in Fig. 2, part of the lading is discharged.

In order to prevent the rear or hinged edge of the door from deflecting I provide a beam 6 which preferably terminates adjacent the oppositely disposed hinges 4 and a bracket 8 is positioned below this beam and preferably extends rearwardly to the rear stiffening flange 8 of the door. A shelf 9 is provided on the center construction which supports the door between the hinges. This

shelf is positioned so that it supports the door when it is in closed position only.

This shelf may be an integral part of the center construction or a separate member 9, as illustrated.

The beam 6 preferably rests upon the shelf but when it is impractical to position the beam near the rear edge, or hinged edge of the door, I provide the bracket 8 which transmits the load from the beam to the shelf 9.

The accompanying drawings illustrate the preferred form of the invention, though it is to be understood that the invention is not limited to the exact details of construction shown and described, as it is obvious that various modifications thereof within the scope of the claims will occur to persons skilled in the art.

I claim:

1. In a railway car of the dumping type having a center sill construction, a door attached to said center construction by a pair of hinges, a beam secured to the door adjacent the hinged edge thereof and extending substantially between the hinges, a bracket secured to said beam, and a shelf upon the center construction which supports the bracket when the door is in closed position.

2. In a railway car of the dumping type having a center sill construction, a door attached to said center construction by a pair of hinges, and means between the hinges to support the door upon the center construction in closed position only.

AUGUST W. L. HARTBAUER.
